UNITED STATES PATENT OFFICE.

EDWARD J. SHUR, OF NEW ORLEANS, LOUISIANA.

VENTILATOR.

1,249,840.

Specification of Letters Patent.

Patented Dec. 11, 1917.

Application filed November 11, 1916. Serial No. 130,815.

To all whom it may concern:

Be it known that I, EDWARD J. SHUR, a citizen of the United States, residing at New Orleans, in the parish of Orleans and State 5 of Louisiana, have invented new and useful Improvements in Ventilators, of which the following is a specification.

My invention pertains to ventilators for cars, more especially refrigerator cars; and 10 it consists in a peculiarly constructed and practically advantageous adjustable ventilator, designed more particularly for use on the body of the refrigerator car constituting the subject of my contemporary application, 15 filed September 18, 1915, Serial Number 51,425.

The present invention will be fully understood from the following description and claim when the same are read in connection 20 with the drawings, accompanying and forming part of this specification, in which:

Figure 1 is a side elevation showing my novel ventilator as properly applied and with the hood in its operative position.

25 Fig. 2 is a longitudinal, vertical section of the same.

Fig. 3 is a top plan view illustrating the hood as thrown back to uncover the opening that it normally controls.

30 Similar numerals of reference designate corresponding parts in all of the views of the drawings.

The car body 1 is provided in its top wall with an opening 2, bordered by an upstanding 35 flange 3, but otherwise the said body may be of any desired construction and type without affecting my present invention.

Hinged at 4 to the body 1 is the base 5 of the ventilator; the said base being of 40 angular form in vertical section so as to contain a rectangular frame 6 which is provided at its underside with a gasket 7, designed to bear on the metallic lining 8 of the opening 2 and thereby render the closure air tight. 45 when the ventilator is closed. The frame 6 is secured in the frame 5 in any approved manner, and it serves, in turn, to hold the flange 9 of the ventilator hood 10 against the horizontally-disposed portion of the base 5 with 50 a view to strongly connecting the said hood with the base.

Any suitable means may be employed for detachably fastening the ventilator in its working position; the fastener 11 being 55 shown by way of example as a type that is adapted to be used in combination with a

padlock so as to prevent an unauthorized person entering the car through the opening 2.

As shown in Figs. 2 and 3, the hood 10 is 60 provided with a front wall, the upper portion of which and the top of the hood describe a part of a circle, as indicated by 12. In the said circular wall is formed an opening 13, which is controlled by a guard 14, 65 of reticulated material, fixed to the wall 12 and curved in conformity thereto. At opposite sides of the opening 13 and immediately in front of the guard 14 are guides 15 which describe a part of a circle, as clearly shown 70 in Fig. 2. Movable in the said guides 15 is a curvilinear imperforate closure plate 16 which when closed is manifestly adapted to prevent the passage of air through the guarded opening 13. A curvilinear perforated bar 17 is fixed to the front of the hood 10 above and below the opening 13, and on the front of the lower portion of the closure plate 16 is fixed a bifurcated arm 18, which receives and is movable freely on the bar 17. 75 The said arm 18 is provided with transverse apertures 19 designed to be registered with the apertures of the bar 17 so as to receive a fastening pin 20 that is connected with the arm 18 through the medium of a chain 21. 80 By virtue of this provision it is manifest the closure plate 16 may be closed to a greater or less extent, according to the volume of air it is desired to let into the car; also, that the said closure plate may be adjustably fixed 85 in the position in which it is placed.

On the hood is a handle 22, through the medium of which the hood may, when unfastened, be swung backwardly and downwardly into the position shown in Fig. 3 so 90 as to leave the opening 2 entirely uncovered. From this it follows that the opening 2 may be utilized for the convenient placing of ice or any other substance desired in the car body.

100 It will be gathered from the foregoing that my novel ventilator is easily adjusted and is highly efficient for the purposes ascribed to it; also, that the ventilator is well adapted to withstand the rough usage to 105 which car appurtenances are ordinarily subjected.

Having described my invention, what I claim and desire to secure by Letters Patent, is:

110 The combination of a body having an opening in its top wall and an upstanding

flange bordering said opening, and a ventilator comprising a base and a hood having an opening and means for controlling said opening; the said base being of angular form 5 in vertical section and hinged to the body in position to receive said upstanding flange, and the hood having a flange disposed under the horizontal portion of the base, and a frame secured in the base and opposed to the 10 flange of the hood and having at its under

side a gasket opposed to the upper end of said upstanding flange of the body.

In testimony whereof I have hereunto set my hand in presence of two subscribing witnesses.

EDWARD J. SHUR.
